UNITED STATES PATENT OFFICE

158,079

WALL CLOCK

Samuel Kamin, Lima, Ohio, assignor to Neon
Products, Inc., Lima, Ohio, a corporation of
Ohio

Application March 23, 1949, Serial No. 1,568

Term of patent 14 years

(Cl. D42—7)

To all whom it may concern:

Be it known that I, Samuel Kamin, a citizen of the United States of America, residing at Lima, in the county of Allen, State of Ohio, have invented a new, original, and ornamental Design for a Wall Clock, of which the following is a specification, reference being made to the accompanying drawing, forming part thereof.

Figure 1 is a view in front elevation of a wall clock, showing my new design.

Fig. 2 is a view in side elevation of the clock.

I claim:

The ornamental design for a wall clock, as shown.

SAMUEL KAMIN.
